(57) **CLAIM**

The ornamental design for a charger for a electronic devices, as shown and described.

DESCRIPTION

FIG. 1 is a front, top, and left side perspective view of a charger for electronic devices showing our new design;

FIG. 2 is a rear, top and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, top and left side perspective view of the charger for electronic devices of FIG. 1, shown in a condition of use.

In the drawings, the broken lines on the charger for electronic devices depict portions of the charger that form no part of the claimed design. In FIG. 9, the broken lines showing a mobile phone, an earbud case, and a cord depict environmental subject matter only, and form no part of the claimed design.

1 Claim, 9 Drawing Sheets
